UNITED STATES PATENT OFFICE

EDWARD SEAVER, OF NEEDHAM, MASSACHUSETTS

HEAT EXCHANGE APPARATUS

Application filed November 9, 1928. Serial No. 318,253.

The present invention relates to heat exchange apparatus and methods of assembling the same.

In heat exchange apparatus employing 5 water tubes, each tube is subject at the entrance end to corrosive and erosive effects of the water. The corrosion at the entrance end of the tube follows from the fact that the incoming water does not completely fill 10 the tube but enters in a constricted stream which permits a pocket of air or other gases to act upon the tube. The turbulence resulting from this constricted flow gives rise to an erosive action. Since the tubes are 15 necessarily made as thin as possible to afford high capacity for heat transfer, the wear on the entrance end of each tube is considerable, necessitating not only a heavy expense for replacement of the tubes themselves, but also because of the frequent shutdowns, a loss of use of the equipment. An 20 added difficulty arises from the use of packed connections, which are sometimes employed, in that the necessary clearance 25 between the tube and the ferrule sets up additional turbulence, and also provides a space for the deposit of silt or scale which increases the corrosive action.

The principal object of the present invention is to provide a water tube assembly and 30 method of making the same whereby the detrimental action of the water on the tubes is substantially eliminated.

A further object of the invention is to 35 provide a water tube assembly in which corrosive and erosive actions, if they occur, are ineffective to attack the relatively thin tube itself and are localized in a part which is able to withstand the wear and which 40 may, if necessary, be readily replaced.

With these objects in view, the present invention consists in the heat exchange apparatus and methods of assembling the same hereinafter described and particularly defined in the claims.

In the accompanying drawings, Fig. 1 is 45 a horizontal section of a portion of the heat exchange apparatus, such as a condenser, embodying the features of the present invention;

Fig. 2 is a horizontal sectional detail view showing the preferred form of the present invention;

Fig. 3 is a detail view showing a modified 55 form of the invention;

Fig. 4 is a detail view showing another modified form of the invention;

Fig. 5 is a still further modification of a 60 type of construction adapted for existing installations; and

Fig. 6 is a modification of the construction shown in Fig. 5.

The illustrated embodiment of the invention comprises a surface condenser comprising a bank of tubes through which the cooling water flows and about the exterior of which the steam is passed. Referring to Fig. 1, the apparatus comprises an entrance tube sheet 2, an exit tube sheet 4, and a bank of tubes 6 connected between the tube sheets. 65 The tubes are received in the exit sheet 4 by means of ferrules 8 cooperating with a metallic packing 10. The construction at the exit end of the tubes is such as to provide for expansion upon changes in temperature. Since the detrimental effects of the water are not apparent to any appreciable extent at the exit end, the construction thus far described is not of primary importance, and any usual or preferred form of attaching means for the exit ends of the tubes may 70 be employed.

The water is conducted to the tubes at 75 their entrance ends through guiding or entrance nozzles 12. In the form of the invention, as shown in Fig. 2, each entrance nozzle 12 comprises a tubular body extending outwardly from the tube sheet to conduct water from the water box into the tube. The nozzle is of considerable thickness compared to the thickness of the tube. The 80 tube sheet is formed with a threaded recess in which the exteriorly threaded end 14 of the nozzle is received. The tube 6 projects into a tube-receiving aperture formed in the tube sheet, as indicated at 16, this aperture forming a continuation of the larger nozzle-receiving recess. The end of the nozzle abuts the entrance end of the tube at the 85 joint, indicated at 18, and the inner end of 90 the tube sheet, indicated at 20, abuts the outer end of the tube at the joint. The tube sheet 4 is secured to the tube sheet 2 by means of 95 bolts 22, and the tube sheet 2 is secured to the water box 24 by means of bolts 26. The water box 24 is secured to the tube sheet 2 by means of bolts 28. The water box 24 is provided with a water inlet 30 and a water outlet 32. The water inlet 30 is connected to a water inlet pipe 34 which is connected to a water inlet 36. The water outlet 32 is connected to a water outlet pipe 38 which is connected to a water outlet 40. The water inlet 36 is connected to a water inlet pipe 42 which is connected to a water inlet 44. The water outlet 40 is connected to a water outlet pipe 46 which is connected to a water outlet 48. The water inlet 44 is connected to a water inlet pipe 50 which is connected to a water inlet 52. The water outlet 48 is connected to a water outlet pipe 54 which is connected to a water outlet 56. The water inlet 52 is connected to a water inlet pipe 58 which is connected to a water inlet 60. The water outlet 56 is connected to a water outlet pipe 62 which is connected to a water outlet 64. The water inlet 60 is connected to a water inlet pipe 66 which is connected to a water inlet 68. The water outlet 64 is connected to a water outlet pipe 70 which is connected to a water outlet 72. The water inlet 68 is connected to a water inlet pipe 74 which is connected to a water inlet 76. The water outlet 72 is connected to a water outlet pipe 80 which is connected to a water outlet 82. The water inlet 76 is connected to a water inlet pipe 84 which is connected to a water inlet 86. The water outlet 82 is connected to a water outlet pipe 90 which is connected to a water outlet 92. The water inlet 86 is connected to a water inlet pipe 94 which is connected to a water inlet 96. The water outlet 92 is connected to a water outlet pipe 100 which is connected to a water outlet 102. The water inlet 96 is connected to a water inlet pipe 104 which is connected to a water inlet 106. The water outlet 102 is connected to a water outlet pipe 110 which is connected to a water outlet 112. The water inlet 106 is connected to a water inlet pipe 114 which is connected to a water inlet 116. The water outlet 112 is connected to a water outlet pipe 120 which is connected to a water outlet 122. The water inlet 116 is connected to a water inlet pipe 124 which is connected to a water inlet 126. The water outlet 122 is connected to a water outlet pipe 130 which is connected to a water outlet 132. The water inlet 126 is connected to a water inlet pipe 134 which is connected to a water inlet 136. The water outlet 132 is connected to a water outlet pipe 140 which is connected to a water outlet 142. The water inlet 136 is connected to a water inlet pipe 144 which is connected to a water inlet 146. The water outlet 142 is connected to a water outlet pipe 150 which is connected to a water outlet 152. The water inlet 146 is connected to a water inlet pipe 154 which is connected to a water inlet 156. The water outlet 152 is connected to a water outlet pipe 160 which is connected to a water outlet 162. The water inlet 156 is connected to a water inlet pipe 164 which is connected to a water inlet 166. The water outlet 162 is connected to a water outlet pipe 170 which is connected to a water outlet 172. The water inlet 166 is connected to a water inlet pipe 174 which is connected to a water inlet 176. The water outlet 172 is connected to a water outlet pipe 180 which is connected to a water outlet 182. The water inlet 176 is connected to a water inlet pipe 184 which is connected to a water inlet 186. The water outlet 182 is connected to a water outlet pipe 190 which is connected to a water outlet 192. The water inlet 186 is connected to a water inlet pipe 194 which is connected to a water inlet 196. The water outlet 192 is connected to a water outlet pipe 200 which is connected to a water outlet 202. The water inlet 196 is connected to a water inlet pipe 204 which is connected to a water inlet 206. The water outlet 202 is connected to a water outlet pipe 210 which is connected to a water outlet 212. The water inlet 206 is connected to a water inlet pipe 214 which is connected to a water inlet 216. The water outlet 212 is connected to a water outlet pipe 220 which is connected to a water outlet 222. The water inlet 216 is connected to a water inlet pipe 224 which is connected to a water inlet 226. The water outlet 222 is connected to a water outlet pipe 230 which is connected to a water outlet 232. The water inlet 226 is connected to a water inlet pipe 234 which is connected to a water inlet 236. The water outlet 232 is connected to a water outlet pipe 240 which is connected to a water outlet 242. The water inlet 236 is connected to a water inlet pipe 244 which is connected to a water inlet 246. The water outlet 242 is connected to a water outlet pipe 250 which is connected to a water outlet 252. The water inlet 246 is connected to a water inlet pipe 254 which is connected to a water inlet 256. The water outlet 252 is connected to a water outlet pipe 260 which is connected to a water outlet 262. The water inlet 256 is connected to a water inlet pipe 264 which is connected to a water inlet 266. The water outlet 262 is connected to a water outlet pipe 270 which is connected to a water outlet 272. The water inlet 266 is connected to a water inlet pipe 274 which is connected to a water inlet 276. The water outlet 272 is connected to a water outlet pipe 280 which is connected to a water outlet 282. The water inlet 276 is connected to a water inlet pipe 284 which is connected to a water inlet 286. The water outlet 282 is connected to a water outlet pipe 290 which is connected to a water outlet 292. The water inlet 286 is connected to a water inlet pipe 294 which is connected to a water inlet 296. The water outlet 292 is connected to a water outlet pipe 300 which is connected to a water outlet 302. The water inlet 296 is connected to a water inlet pipe 304 which is connected to a water inlet 306. The water outlet 302 is connected to a water outlet pipe 310 which is connected to a water outlet 312. The water inlet 306 is connected to a water inlet pipe 314 which is connected to a water inlet 316. The water outlet 312 is connected to a water outlet pipe 320 which is connected to a water outlet 322. The water inlet 316 is connected to a water inlet pipe 324 which is connected to a water inlet 326. The water outlet 322 is connected to a water outlet pipe 330 which is connected to a water outlet 332. The water inlet 326 is connected to a water inlet pipe 334 which is connected to a water inlet 336. The water outlet 332 is connected to a water outlet pipe 340 which is connected to a water outlet 342. The water inlet 336 is connected to a water inlet pipe 344 which is connected to a water inlet 346. The water outlet 342 is connected to a water outlet pipe 350 which is connected to a water outlet 352. The water inlet 346 is connected to a water inlet pipe 354 which is connected to a water inlet 356. The water outlet 352 is connected to a water outlet pipe 360 which is connected to a water outlet 362. The water inlet 356 is connected to a water inlet pipe 364 which is connected to a water inlet 366. The water outlet 362 is connected to a water outlet pipe 370 which is connected to a water outlet 372. The water inlet 366 is connected to a water inlet pipe 374 which is connected to a water inlet 376. The water outlet 372 is connected to a water outlet pipe 380 which is connected to a water outlet 382. The water inlet 376 is connected to a water inlet pipe 384 which is connected to a water inlet 386. The water outlet 382 is connected to a water outlet pipe 390 which is connected to a water outlet 392. The water inlet 386 is connected to a water inlet pipe 394 which is connected to a water inlet 396. The water outlet 392 is connected to a water outlet pipe 400 which is connected to a water outlet 402. The water inlet 396 is connected to a water inlet pipe 404 which is connected to a water inlet 406. The water outlet 402 is connected to a water outlet pipe 410 which is connected to a water outlet 412. The water inlet 406 is connected to a water inlet pipe 414 which is connected to a water inlet 416. The water outlet 412 is connected to a water outlet pipe 420 which is connected to a water outlet 422. The water inlet 416 is connected to a water inlet pipe 424 which is connected to a water inlet 426. The water outlet 422 is connected to a water outlet pipe 430 which is connected to a water outlet 432. The water inlet 426 is connected to a water inlet pipe 434 which is connected to a water inlet 436. The water outlet 432 is connected to a water outlet pipe 440 which is connected to a water outlet 442. The water inlet 436 is connected to a water inlet pipe 444 which is connected to a water inlet 446. The water outlet 442 is connected to a water outlet pipe 450 which is connected to a water outlet 452. The water inlet 446 is connected to a water inlet pipe 454 which is connected to a water inlet 456. The water outlet 452 is connected to a water outlet pipe 460 which is connected to a water outlet 462. The water inlet 456 is connected to a water inlet pipe 464 which is connected to a water inlet 466. The water outlet 462 is connected to a water outlet pipe 470 which is connected to a water outlet 472. The water inlet 466 is connected to a water inlet pipe 474 which is connected to a water inlet 476. The water outlet 472 is connected to a water outlet pipe 480 which is connected to a water outlet 482. The water inlet 476 is connected to a water inlet pipe 484 which is connected to a water inlet 486. The water outlet 482 is connected to a water outlet pipe 490 which is connected to a water outlet 492. The water inlet 486 is connected to a water inlet pipe 494 which is connected to a water inlet 496. The water outlet 492 is connected to a water outlet pipe 500 which is connected to a water outlet 502. The water inlet 496 is connected to a water inlet pipe 504 which is connected to a water inlet 506. The water outlet 502 is connected to a water outlet pipe 510 which is connected to a water outlet 512. The water inlet 506 is connected to a water inlet pipe 514 which is connected to a water inlet 516. The water outlet 512 is connected to a water outlet pipe 520 which is connected to a water outlet 522. The water inlet 516 is connected to a water inlet pipe 524 which is connected to a water inlet 526. The water outlet 522 is connected to a water outlet pipe 530 which is connected to a water outlet 532. The water inlet 526 is connected to a water inlet pipe 534 which is connected to a water inlet 536. The water outlet 532 is connected to a water outlet pipe 540 which is connected to a water outlet 542. The water inlet 536 is connected to a water inlet pipe 544 which is connected to a water inlet 546. The water outlet 542 is connected to a water outlet pipe 550 which is connected to a water outlet 552. The water inlet 546 is connected to a water inlet pipe 554 which is connected to a water inlet 556. The water outlet 552 is connected to a water outlet pipe 560 which is connected to a water outlet 562. The water inlet 556 is connected to a water inlet pipe 564 which is connected to a water inlet 566. The water outlet 562 is connected to a water outlet pipe 570 which is connected to a water outlet 572. The water inlet 566 is connected to a water inlet pipe 574 which is connected to a water inlet 576. The water outlet 572 is connected to a water outlet pipe 580 which is connected to a water outlet 582. The water inlet 576 is connected to a water inlet pipe 584 which is connected to a water inlet 586. The water outlet 582 is connected to a water outlet pipe 590 which is connected to a water outlet 592. The water inlet 586 is connected to a water inlet pipe 594 which is connected to a water inlet 596. The water outlet 592 is connected to a water outlet pipe 600 which is connected to a water outlet 602. The water inlet 596 is connected to a water inlet pipe 604 which is connected to a water inlet 606. The water outlet 602 is connected to a water outlet pipe 610 which is connected to a water outlet 612. The water inlet 606 is connected to a water inlet pipe 614 which is connected to a water inlet 616. The water outlet 612 is connected to a water outlet pipe 620 which is connected to a water outlet 622. The water inlet 616 is connected to a water inlet pipe 624 which is connected to a water inlet 626. The water outlet 622 is connected to a water outlet pipe 630 which is connected to a water outlet 632. The water inlet 626 is connected to a water inlet pipe 634 which is connected to a water inlet 636. The water outlet 632 is connected to a water outlet pipe 640 which is connected to a water outlet 642. The water inlet 636 is connected to a water inlet pipe 644 which is connected to a water inlet 646. The water outlet 642 is connected to a water outlet pipe 650 which is connected to a water outlet 652. The water inlet 646 is connected to a water inlet pipe 654 which is connected to a water inlet 656. The water outlet 652 is connected to a water outlet pipe 660 which is connected to a water outlet 662. The water inlet 656 is connected to a water inlet pipe 664 which is connected to a water inlet 666. The water outlet 662 is connected to a water outlet pipe 670 which is connected to a water outlet 672. The water inlet 666 is connected to a water inlet pipe 674 which is connected to a water inlet 676. The water outlet 672 is connected to a water outlet pipe 680 which is connected to a water outlet 682. The water inlet 676 is connected to a water inlet pipe 684 which is connected to a water inlet 686. The water outlet 682 is connected to a water outlet pipe 690 which is connected to a water outlet 692. The water inlet 686 is connected to a water inlet pipe 694 which is connected to a water inlet 696. The water outlet 692 is connected to a water outlet pipe 700 which is connected to a water outlet 702. The water inlet 696 is connected to a water inlet pipe 704 which is connected to a water inlet 706. The water outlet 702 is connected to a water outlet pipe 710 which is connected to a water outlet 712. The water inlet 706 is connected to a water inlet pipe 714 which is connected to a water inlet 716. The water outlet 712 is connected to a water outlet pipe 720 which is connected to a water outlet 722. The water inlet 716 is connected to a water inlet pipe 724 which is connected to a water inlet 726. The water outlet 722 is connected to a water outlet pipe 730 which is connected to a water outlet 732. The water inlet 726 is connected to a water inlet pipe 734 which is connected to a water inlet 736. The water outlet 732 is connected to a water outlet pipe 740 which is connected to a water outlet 742. The water inlet 736 is connected to a water inlet pipe 744 which is connected to a water inlet 746. The water outlet 742 is connected to a water outlet pipe 750 which is connected to a water outlet 752. The water inlet 746 is connected to a water inlet pipe 754 which is connected to a water inlet 756. The water outlet 752 is connected to a water outlet pipe 760 which is connected to a water outlet 762. The water inlet 756 is connected to a water inlet pipe 764 which is connected to a water inlet 766. The water outlet 762 is connected to a water outlet pipe 770 which is connected to a water outlet 772. The water inlet 766 is connected to a water inlet pipe 774 which is connected to a water inlet 776. The water outlet 772 is connected to a water outlet pipe 780 which is connected to a water outlet 782. The water inlet 776 is connected to a water inlet pipe 784 which is connected to a water inlet 786. The water outlet 782 is connected to a water outlet pipe 790 which is connected to a water outlet 792. The water inlet 786 is connected to a water inlet pipe 794 which is connected to a water inlet 796. The water outlet 792 is connected to a water outlet pipe 800 which is connected to a water outlet 802. The water inlet 796 is connected to a water inlet pipe 804 which is connected to a water inlet 806. The water outlet 802 is connected to a water outlet pipe 810 which is connected to a water outlet 812. The water inlet 806 is connected to a water inlet pipe 814 which is connected to a water inlet 816. The water outlet 812 is connected to a water outlet pipe 820 which is connected to a water outlet 822. The water inlet 816 is connected to a water inlet pipe 824 which is connected to a water inlet 826. The water outlet 822 is connected to a water outlet pipe 830 which is connected to a water outlet 832. The water inlet 826 is connected to a water inlet pipe 834 which is connected to a water inlet 836. The water outlet 832 is connected to a water outlet pipe 840 which is connected to a water outlet 842. The water inlet 836 is connected to a water inlet pipe 844 which is connected to a water inlet 846. The water outlet 842 is connected to a water outlet pipe 850 which is connected to a water outlet 852. The water inlet 846 is connected to a water inlet pipe 854 which is connected to a water inlet 856. The water outlet 852 is connected to a water outlet pipe 860 which is connected to a water outlet 862. The water inlet 856 is connected to a water inlet pipe 864 which is connected to a water inlet 866. The water outlet 862 is connected to a water outlet pipe 870 which is connected to a water outlet 872. The water inlet 866 is connected to a water inlet pipe 874 which is connected to a water inlet 876. The water outlet 872 is connected to a water outlet pipe 880 which is connected to a water outlet 882. The water inlet 876 is connected to a water inlet pipe 884 which is connected to a water inlet 886. The water outlet 882 is connected to a water outlet pipe 890 which is connected to a water outlet 892. The water inlet 886 is connected to a water inlet pipe 894 which is connected to a water inlet 896. The water outlet 892 is connected to a water outlet pipe 900 which is connected to a water outlet 902. The water inlet 896 is connected to a water inlet pipe 904 which is connected to a water inlet 906. The water outlet 902 is connected to a water outlet pipe 910 which is connected to a water outlet 912. The water inlet 906 is connected to a water inlet pipe 914 which is connected to a water inlet 916. The water outlet 912 is connected to a water outlet pipe 920 which is connected to a water outlet 922. The water inlet 916 is connected to a water inlet pipe 924 which is connected to a water inlet 926. The water outlet 922 is connected to a water outlet pipe 930 which is connected to a water outlet 932. The water inlet 926 is connected to a water inlet pipe 934 which is connected to a water inlet 936. The water outlet 932 is connected to a water outlet pipe 940 which is connected to a water outlet 942. The water inlet 936 is connected to a water inlet pipe 944 which is connected to a water inlet 946. The water outlet 942 is connected to a water outlet pipe 950 which is connected to a water outlet 952. The water inlet 946 is connected to a water inlet pipe 954 which is connected to a water inlet 956. The water outlet 952 is connected to a water outlet pipe 960 which is connected to a water outlet 962. The water inlet 956 is connected to a water inlet pipe 964 which is connected to a water inlet 966. The water outlet 962 is connected to a water outlet pipe 970 which is connected to a water outlet 972. The water inlet 966 is connected to a water inlet pipe 974 which is connected to a water inlet 976. The water outlet 972 is connected to a water outlet pipe 980 which is connected to a water outlet 982. The water inlet 976 is connected to a water inlet pipe 984 which is connected to a water inlet 986. The water outlet 982 is connected to a water outlet pipe 990 which is connected to a water outlet 992. The water inlet 986 is connected to a water inlet pipe 994 which is connected to a water inlet 996. The water outlet 992 is connected to a water outlet pipe 1000 which is connected to a water outlet 1002.

the nozzle is therefore preferably formed with an accurate shoulder in order to assure a smooth fit where the tube and nozzle abut. At its inner end, the nozzle is of a diameter as nearly equal as possible to the internal diameter of the tube, and at its entrance end the nozzle is rounded, as shown at 20, to form a substantial stream line entrance for the water. The nozzle is slotted at 22 to afford means for threading the nozzle into the tube sheet.

After assembly of the tubes and nozzles in the tube sheet, an expanding tool is run into each nozzle and is caused to expand the metal of the tube and nozzle over approximately the space indicated at 24. This expanding operation is carried out by an expander of any usual form. It acts to force the metal of the tube into engagement with the tube sheet, thus forming a tight joint to prevent leakage of water into the steam space, and in addition to present a smooth and continuous inner bore to the water at the junction of the nozzle and tube. The tubes and nozzles are of metal brass or steel alloys, which have some ductility, and the expanding operation, therefore, causes a sufficient flow of metal to force the tube and nozzle into close engagement with each other. Even though the tubes and nozzles are made with a slight tolerance or may be slightly out of round at the ends, the expanding action causes such a flow of metal as practical to smooth the joint between the tube and nozzle against any irregularities in surface. The expanding action also serves to force the metal of the nozzle into engagement with the tube sheet along the threads. Inasmuch as the nozzle is of relatively ductile material, this expanding operation effects a substantial bond which is mechanically strong and also resists leakage of water into the joint. The ductility of the nozzle, however, permits removal thereof from the tube sheet whenever necessary, the threads on the tube sheet being unharmed by the expanding operation.

It will be seen that the entrance nozzle is so designed at its entrance end that it substantially conforms to the path of water flow. The corrosive effect of an air pocket is therefore largely eliminated. Moreover, the turbulence of flow is considerably reduced and as a result, the erosive action is minimized. The nozzle is of such a length that corrosive and erosive actions, if they occur at all, are localized in the nozzle itself and do not reach into the tube. Since the nozzle is of relatively heavy material, the wear occasioned by the water is of relatively small importance and when it does become of consequence, the nozzle can be readily replaced without removal of the tube. Upon replacement of a nozzle, the new nozzle is threaded into the tube sheet

until it firmly abuts the end of the tube and another expanding operation is performed to make a smooth tight joint between the nozzle and the tube. The joint 18 is in all cases smooth and continuous, and presents no irregularities to permit a deposit of silt or scale. The joint that may be obtained by an expanding operation is such as to make an apparently continuous length of water passage from the entrance end of the nozzle to the exit end of the tube.

In the construction shown in Fig. 3, the entrance tube sheet 2 is provided with a threaded nozzle-receiving recess as in the construction described above. The tube 26, however, is positioned in the tube sheet so that its end is substantially flush with the outer surface of the tube sheet. The nozzle 28 is in form similar to the nozzle 12 described above, having an exteriorly threaded end 30 to be received in the tube sheet. The interior of the nozzle has a threaded counterbore 32 to receive the end of the tube 26. The end of the tube abuts a shoulder 34 of the nozzle, the tube and nozzle being of equal internal diameters to afford a smooth uninterrupted joint. After assembly of the parts, an expanding tool is caused to operate over the length indicated approximately at 36. The expanding action is to force the tube into engagement with the tube sheet and with the internal threads of the nozzle, and to make a smooth, tight joint between the tube and nozzle. The nozzle itself is forced into engagement with the tube sheet as in the construction previously described.

In the construction shown in Fig. 4, the entrance tube sheet is shown at 40 and the tube 42 extends completely through the tube sheet. The entrance nozzle 44 is of the same general form as the nozzle previously described, but is not threaded. The inner end of the nozzle is counterbored to receive the entrance end of the tube, the shoulder 46 of the counterbore abutting tightly against the end of the tube. After assembly, the expanding tool operates over the length of tube and nozzle, indicated at 48, as well as on the length of tube engaging with the tube sheet. In this modification, as in the other forms of the invention, a smooth, continuous and tight joint is provided at the shoulder 46. The construction is one which may be applied to existing plants with very little difficulty because of the fact that no machining of the tube sheet is necessary.

The construction shown in Figs. 5 and 6 is particularly adapted to existing installations in which it is desired to replace the usual ferrule surrounding the tube end. In the construction shown in Fig. 5, the tube end projects within the opening in the tube sheet, and is surrounded intermediate the opposite sides of the tube sheet by a packing 50, preferably of fibrous material. A

5 nozzle 52 is threaded at 54 within the recess already present in the tube sheet, the shoulered portions 56 of the nozzle abutting the outer surface of the tube sheet. Thereafter the tube 6 is expanded into engagement with the packing, the tube sheet, and the inner bore of the nozzle throughout the region 58 to seal against leakage and provide a smooth, continuous, inner bore, leaving no gap at the junction between the tube end and the inner shoulder 60 formed upon the nozzle. The construction shown in Fig. 6 10 is similar to that of Fig. 5, with the single exception that sufficient thickness is allowed at the inner end of the nozzle for the provision of internal threads 62 into which the material of the tube end 6 is partially flowed during the process of expanding the tube end into the nozzle and surrounding tube 15 sheet.

20 It will be evident from the foregoing description that all of the herein described constructions, whether applied to existing forms of water tube assemblies or developed as new assemblies, embodying the characteristic feature of an entrance nozzle having a substantially greater wall thickness than that of the conventional tube and of sufficient length to confine turbulence and 25 eddy currents within the region of the nozzle, the junction between the nozzle and the abutting end of the tube being free from gaps, shoulders, or projections to form localized eddy currents, and 30 presenting a smooth, continuous and unbroken inner bore for the flow of water from the entrance point of the nozzle to the tube intermediate its ends. With this construction, it will be evident that the erosive 35 effects of water turbulence and eddy currents are practically removed from the tube 40 structure. Correspondingly, the tube structure may be made with a desirably thin wall to facilitate heat exchange, the corrosive 45 effects upon the tube wall being reduced and minimized, due to continuity of flow therethrough, and the confinement of localized actions, if any, to the region of the nozzle.

45 What is claimed is:

50 1. Heat exchange apparatus comprising an entrance tube sheet, water tubes secured in the tube sheet, an entrance nozzle for each tube to guide water to the tube and extending outwardly beyond the tube sheet, the 55 nozzle being of sufficient length to confine turbulence, the tube and nozzle being of the same internal diameter and abutting each other, the metal of the tube and nozzle being expanded to form a smooth and continuous inner bore.

60 2. Heat exchange apparatus comprising a tube sheet, water tubes secured in the tube sheet, an entrance nozzle for each tube, the tube and nozzle having abutting surfaces 65 and being of the same internal diameter at

their junction, the nozzle having relatively thick walls compared to the tube to resist corrosion, and the tube and nozzle forming a smooth and continuous inner bore to permit uninterrupted flow of water at their 70 junction.

3. Heat exchange apparatus comprising a tube sheet, water tubes secured in the tube sheet, an entrance nozzle for each tube extending outwardly beyond the tube sheet, 75 the tube and nozzle abutting each other and being expanded together to form a smooth, continuous surface at their junction, the nozzle being of considerable thickness compared to that of the tube and having a 80 rounded inlet to guide the water interiorly of the nozzle.

4. Heat exchange apparatus comprising an entrance tube sheet and water tubes secured in the tube sheet, an entrance nozzle 85 for each tube having threaded engagement with the tube sheet and having a surface abutting the end of the tube, the nozzle extending outwardly beyond the tube sheet and being of sufficient length to confine 90 turbulence, the tube and nozzle being expanded to form a smooth and continuous surface at their junction.

5. Heat exchange apparatus comprising an entrance tube sheet having apertures to 95 receive tubes and a threaded nozzle-receiving recess associated with each tube aperture, water tubes secured in the apertures, a nozzle having a threaded end received in the nozzle-receiving recess and abutting the 100 entrance end of each tube, the abutting surfaces of the tubes and nozzles forming smooth and uninterrupted junctions of uniform diameter to permit uniform flow of water.

6. Heat exchange apparatus comprising an entrance tube sheet having a plurality of tube apertures and a plurality of nozzle-receiving recesses extending partially through the tube sheet, water tubes secured in the 110 tube apertures and extending slightly into the nozzle recess, a nozzle for each tube threaded in the tube sheet and having a shoulder abutting the end of the tube to form a smooth, continuous junction of uniform diameter.

7. A method of assembling heat exchange apparatus which consists in positioning a water tube in a tube sheet with its end between the opposite sides of the tube sheet, 120 threading an entrance nozzle in the tube sheet with its end abutting the entrance end of the tube, and expanding the metal of the tube and nozzle to form a smooth and continuous surface at the junction of the tube 125 and nozzle.

8. Heat exchange apparatus comprising an entrance tube sheet, a series of water tubes mounted in the sheet, an entrance nozzle for each tube to guide water to the 130

5 tube extending outwardly beyond the sheet, the tube and nozzle having the same internal diameter, and the nozzle provided with a recessed portion in which the end of the tube is expanded to form a smooth and continuous inner bore at the junction.

9. Heat exchange apparatus comprising a series of relatively thin wall tubes adapted to convey water therethrough and facilitate heat interchange, an entrance nozzle connected with the entrance end of each tube and having a wall thickness substantially greater than that of the tube, the entrance nozzle being of sufficient length to confine turbulence, due to entering water flow within the region of the nozzle, and presenting, in combination with the tube, a smooth and substantially continuous inner bore for the flow of water therethrough.

10 10. Heat exchange apparatus comprising an entrance tube sheet, a series of water tubes mounted within the sheet, a series of entrance nozzles detachably connected directly to the sheet and extending outwardly therebeyond to provide conduits of substantial length for directing water to the tubes, the interior of each nozzle and connected tube being of the same diameter, and presenting a smooth and substantially continuous inner bore for the flow of water therethrough.
